MULTICATHODE PHOTOTUBE

Ralph W. Engstrom, Lancaster, Pa., assignor to
Radio Corporation of America, a corporation of
Delaware

Application May 29, 1943, Serial No. 489,000

6 Claims. (Cl. 250—165)

1

My invention relates to phototubes and particularly to phototubes incorporating a plurality of photo-electrically sensitive cathodes.

It has been customary in conventional phototubes to provide two or more photocathodes side-by-side and facing in one direction for use either with a single or multiple light source. In certain applications, however, it is desirable to provide a structure suitable for use with a single light source projecting light on the light sensitive structure either from a wide angle or as a spot and to provide a circuit and phototube responsive to relative movement between the light spot and the tube for use as direction indicators. Such applications require very accurate spacing of the electrodes and a very rugged structure so that longitudinal movement and rotation of the phototube with respect to the light spot or its origin produces no displacement of the tube parts either with respect to one another or with respect to the tube envelope.

An object of my invention is to provide a phototube and phototube structure wherein precise alignment of a plurality of photo-electrically sensitive cathodes may be obtained. It is a further object of my invention to provide a more sensitive photo-electric structure for the determination of relative movement of a light source with respect to said structure. It is a still further object to provide a phototube wherein a relatively small displacement of a spot of light incident on the sensitive structure provides a relatively great change in tube sensitivity. It is a still further object to provide a rugged photo-electric tube of the multi-cathode type wherein each of the cathodes is substantially equally sensitive, and a still further object is to provide a tube which is rugged, easy of manufacture and suitable for accurate determination of light source movement.

In accordance with my invention I provide a plurality of photo-electrically sensitive cathodes surrounding a centrally disposed tube axis and disposed such that the cathode areas projected on a plane normal to the axis are equal and are considerably smaller than the actual cathode areas, and such that the planes of the cathodes intersect at a point outside the tube envelope. In addition, each of the cathodes is insulated from the adjacent cathode so that each may be energized with respect to an anode surrounding and symmetrically disposed with respect to said cathodes and said axis. These and other objects, features and advantages of my invention will become apparent when taken in connection with the accompanying drawing wherein:

5

Figure 1 is a longitudinal view of a phototube made in accordance with my invention with a portion of the envelope cut away to show the internal structure, and

5

Figure 2 is a cross-sectional plan view of the tube of Figure 1 taken along the lines 2—2.

Referring to Figure 1, I have shown an envelope 1 having a stem or press 2 supporting my new and improved multi-cathode and electrode structure axially of the envelope 1 by means of current carrying leads and supports sealed in the press 2. To support the plurality of cathodes I provide transverse insulating members substantially parallel one to another, between which the cathodes and the anode are supported. More particularly, I provide two insulating spacers such as an upper spacer 4 and a lower spacer 5 between which I support four electrically insulated cathodes 6. It will be appreciated that any plurality of such cathodes may be supported in a similar manner and that while I have shown four such cathodes, any reasonable number such as two or more may be used, depending on the specific application for which the tube is designed. The upper spacer 4 which supports the upper portions of the cathodes 6 is provided with a corresponding number 10 of apertures or slots 7 through which the tabs 8, preferably integral with the cathodes, extend, the tabs being bent over on the under side of the spacer 4 as shown at 9. The lower spacer 5 is provided with similar apertures or slots 10 to support the lower edges of the cathodes 6. Consequently, I provide on the cathodes 6, preferably integral with the lower edges thereof, a plurality of tabs 11 which extend through the corresponding apertures in the lower spacer 5. I have shown the cathodes as being of rectangular form with the integral tabs bent over and engaging the apertures in the upper and lower spacers, but it will be appreciated that these cathodes need not be of rectangular form but that they may be trapezoidal in shape with the base portion supported by the spacer 5.

40

45

As shown by the drawing, the points of support for the cathodes on the lower spacer 5 are more remote from the axis 3—3 than are the points of support on the upper spacer 4, so that the surface of the cathodes effectively lies on or forms a truncated pyramidal surface whose apex is without the envelope 1 and lying on the axis 3—3. Thus in accordance with a limited teaching of my invention, I provide a multiple cathode structure surrounding a centrally disposed axis, the cathodes forming in effect the 50 side portions of a right truncated pyramid. How-

ever, I will use the term "truncated pyramid" to include a truncated cone wherein the side portions are curved and lie on or form a truncated conical surface whose apex is without the envelope and on the axis 3—3. Still further in accordance with my invention, I provide an anode common to all of the cathodes preferably lying equally distant from the longitudinal axis about which the cathodes are disposed. More particularly, as shown in the drawing, I provide an anode 12 preferably in the form of a ring surrounding the cathodes 6 at a greater distance from the axis 3—3 than the cathodes and in a position between the two transverse insulating support members such as the spacers 4 and 5. The anode 12 is preferably supported by support wires 13 extending substantially parallel to the axis 3—3 and as far removed from the cathodes as possible. Thus as shown, especially in Figure 2, the support wires 13 may extend transversely from the press 2 and then parallel to the axis 3—3 in a region adjacent at least two of the corners formed between adjacent cathode planes. With such positioning, the support wires 13 produce the minimum of interference or unequal current collection with respect to the cathodes, while at the same time being located without the path of light which, during operation, is incident on the cathodes such as along an optical path coincident with the axis 3—3.

With my improved construction of a multiple cathode phototube it will be appreciated that each of the cathodes may be illuminated equally by a spot of light concentric with the said longitudinal axis, and that the cathodes for such coincidence and with a circular spot receive an equal amount of light assuming uniform distribution of light within the spot. However, with non-coincidence of the spot with the axis, the cathodes receive unequal portions of the light and consequently provide unequal photo-electric currents in the respective cathode circuits. The sensitivity of my device with respect to such movement of the incident light spot with respect to the cathodes is greatly increased by this disposition of the cathodes about the lateral surface of a truncated pyramid because the intercepted light varies at a relatively great rate for differences in the angle of incidence of light from a source near the apex of the pyramidal disposition of the cathodes.

The cathodes may be of any of the well-known types such as the alkali metal treated silver-silver oxide type or of the alkali metal treated antimony, arsenic or bismuth type depending upon the particular spectral range of the light source used in combination with the tube. Thus, for example, the cathodes 6 may be of silver or silver plated base metal oxidized preferably by a glow discharge in oxygen developed between the cathodes and the anode and treated with an alkali metal such as caesium. Following such oxidation, the cathode may be treated by liberating caesium or other alkali metal such as from a pellet of alkali metal compound attached to an activator tab 14 as well known in the art. Alternatively, the cathodes 6 may be of a base metal such as nickel, or of an oxidized chromium containing nickel alloy, coated with a film of antimony or an equivalent element such as ar-

senic or bismuth. This latter type of cathode is particularly suitable for obtaining high photo-electric response when subjected to light over the blue and violet portions of the spectrum, whereas the former type of cathode is particularly suitable for light in the red and infra red portions of the spectrum. The antimony film on the cathodes, if the latter type is used, is similarly treated with an alkali metal such as caesium which may be liberated within the envelope from the activator tab 14.

I claim:

1. A phototube comprising an envelope, a plurality of cathodes and an anode within said envelope, said cathodes lying along surfaces forming a truncated pyramid whose apex is outside said envelope.

2. A phototube comprising an envelope, a plurality of cathodes surrounding a centrally disposed axis, and an anode within said envelope, said cathodes lying along surfaces forming a truncated pyramid whose apex is outside said envelope and on said centrally disposed axis.

3. A phototube comprising an envelope enclosing a plurality of planar cathodes surrounding a centrally disposed axis, the extended surfaces of said cathodes intersecting said axis at a common point without the envelope and an anode surrounding said cathodes and said axis.

4. A phototube comprising an envelope, a plurality of photosensitive cathodes and an anode within said envelope, said cathodes lying along the bounding lateral surfaces of a truncated pyramid whose planes intersect to define a virtual apex of said pyramid without said envelope.

5. A phototube comprising an envelope, a pair of electrode support members lying transversely of said envelope, a plurality of planar cathodes mounted about an axis within said envelope and between said electrode support members, said cathodes lying along the lateral surfaces of a truncated pyramid and an anode surrounding said cathodes between each thereof and said envelope.

6. A phototube comprising an envelope, a pair of apertured electrode support members lying transversely of said envelope, a plurality of planar cathodes mounted about an axis within said envelope, a plurality of integral tabs on each of said cathodes, said tabs engaging the apertures of said support members and being supported thereby, the apertures in said support members being positioned with said cathodes inclined to said axis by substantially the same amount.
